UNITED STATES PATENT OFFICE.

EDDY T. THOMAS, OF NEW YORK, N. Y., ASSIGNOR TO THE GOLD MEDAL SEWING MACHINE COMPANY, OF ORANGE, MASSACHUSETTS.

EMBROIDERING ATTACHMENT FOR SEWING-MACHINES.

SPECIFICATION forming part of Letters Patent No. 243,740, dated July 5, 1881.

Application filed February 26, 1881. (No model.)

To all whom it may concern:

Be it known that I, EDDY T. THOMAS, of New York, county of New York, and State of New York, have invented a new and useful Improvement in Embroidering Attachments for Sewing-Machines, of which the following description, in connection with the accompanying drawings, is a specification.

This invention in sewing-machines has reference to an attachment for producing an embroidery-stitch on top of the cloth, there being combined with the embroidery attachment a zigzag-feeding mechanism, which, operating upon the surface of the material resting upon the cloth-supporting bed of the machine, moves the said material to and fro laterally, thus causing the embroidery thread and stitching to be laid in zigzag lines.

Figure 1 represents, in side elevation, a so-called "New Home" sewing-machine with my improvements attached thereto. Fig. 2 is a partial front elevation thereof. Fig. 3 is a detail of the guide for the forward end of the zigzag-feeding device, the upper end of the guide being attached to the rear side of the head in which the needle-bar reciprocates. Fig. 4 represents in line A a stitch such as the embroidery attachment will make without the zigzag-feeding mechanism, and the line B with it. Fig. 5 is a top view of the presser-foot and the thread-carrying hook located therein on a larger scale; Fig. 6, a detail, showing part of shaft *h* and its pinion; Fig. 7, a detail of eccentric on shaft *l*; Fig. 8, an enlarged detail of the zigzag-feeding device, and Fig. 9 a modification of the zigzag-feeding device; and Fig. 10 is a sectional detail on dotted line *xx*, Fig. 1, but on a smaller scale.

The embroidery attachment herein shown is composed of an annular rotary reciprocating hook, *a*, mounted on and made to loosely surround a short tube, *S*, the said tube being coincident with the needle-hole in the presser-foot. The shank of the hook *a* has upon it a series of teeth, *9*, to be engaged by teeth of a small pinion, *10*, connected with the lower end of a twisted rod, *b*, which, extended up through the slot in a plate, *c*, secured to the lower end of the needle-bar *d*, has its upper end held in

an ear of the bracket *e*, forming part of an upright extended upward from the presser-foot *f*, which is connected with the usual presser-foot bar *g* by a suitable screw, instead of the presser-foot which is used for plain sewing. This embroidery attachment is not of my invention, but is well known in the market as the "Empress Embroiderer Attachment." The annular hook *a* of this attachment lays a silk or other large or colored thread, *12*, upon the upper side of the fabric, in coil or loop form, under the usual descending eye-pointed needle, the thread *13* carried by the needle confining on the fabric the embroidery-thread laid thereon by the annular hook *a*, making a stitch such as represented in the line A, Fig. 5.

In order to produce a line of zigzag embroidery-strokes, such as represented in the line B, the upright shaft *h* of the sewing-machine has been provided with a pinion, *i*, (see detail, Fig. 6,) to engage the toothed wheel *j* on the upright shaft *l*, having its bearings in a yoke, *m*, suitably secured to the cloth-supporting bed *n* of the machine, but so as to be detachable therefrom, if desired. This shaft *l* is provided with an eccentric, *o*, (see detail, Fig. 7,) about which is placed the eccentric-strap *p*, secured to the end of the rod *q*, having attached to its front end the toothed or rough-surfaced zigzag-feeding device *r*, which rests upon the cloth or other material laid on the cloth-supporting bed *n* in front of the presser-foot *f*, the cloth being entered between the latter and the usual cloth-feeding device *s*. (Shown in Fig. 2.)

The forward end of the rod *q* at the rear of the feeding device *r* is embraced and guided by the forked lower end of the guide *t*, adjustably attached by the screw *u* to the rear side of the head *C*, in which the needle-bar is made to reciprocate, as usual. The upright part of the guide *t* has connected with it by screw *w* a spring, *x*, the lower end of which (see Fig. 1) rests upon the rod *q* and holds the zigzag-feeding device *r* down in contact with the surface of the material. The rod *q* is provided with a small loop, *z*, the upper right-angled end of which is made to enter the slot 3 in the guide *t*, the curved finger 4 of a lifter, *5*, pivoted at 6 upon the front side of the bracket *t*, being

extended under the right-angled projection of the said loop 2 to enable the zigzag-feeding device *r* to be lifted, when desired, from the cloth, as represented in Fig. 2.

- 5 The rotary shaft *h* and the pinion *i* thereon, acting upon the toothed wheel *j*, turn the shaft *l* and eccentric *o* thereon, causing the latter to reciprocate the rod *q* and the zigzag-feeding device *r* in the direction of the length of the 10 cloth-supporting bed, and at right angles to the direction of the movement of the material or fabric by the action of the usual feeding device, *s*. The zigzag-feeding device *r* thus moved moves the cloth or material laterally as it is 15 moved forward by the feed *s*, which results in laying the embroidery-thread upon the surface of the fabric in zigzag or waved lines, as represented by the line B, Fig. 5, the needle-thread securing the said embroidery-thread in place.
- 20 Instead of the particular embroidery attachment herein shown I, may employ any well-known equivalent embroidery attachment having a thread-carrying arm to lay the embroidery-thread upon the surface of the material to 25 be caught and held by the thread carried by the usual sewing-needle.
- The zigzag-feeding wheel *r*, instead of having blunt projections, may have pin-points, as in Fig. 9.
- 30 The eccentric-yoke *p*, which embraces the eccentric *o*, will in practice be detachably connected with rod *q* by a screw, 14, (see Fig. 1,) to permit the said yoke to be detached from the eccentric *o*, and the latter to be removed 35 from shaft *l*, to be replaced by another eccentric, of larger size. The diameter of the eccentric, and the speed of rotation of the shaft *l* with relation to the rotation of shaft *h*, moves the zigzag-feeding device a greater or less extent of lateral movement in one and then in 40 the other direction, thus causing the stitches upon the upper surface of the cloth to be extended over a greater or less space or width.

The relative sizes of the pinion *i* and toothed wheel *j* of the embroidery-attachment shaft *l* 45 may be such as to move the zigzag-feeding device and insure the formation of two or more stitches during the time that the feeding device *r* moves the fabric in one and then in the opposite direction. 50

I claim—

1. The independent shaft *l*, its toothed wheel *j*, and the eccentric on the said shaft, combined with the eccentric-strap, rod *q*, and zigzag-feeding device *r*, and with the bracket to guide 55 the rod *q*, substantially as described.
2. The presser-foot and the feeding device *s*, located below and adapted to act on the under surface of the material, combined with the independent laterally-movable feeding device *r*, 60 located above the material in front of the presser-foot, substantially as described.
3. The presser-foot *f* and annular rotary reciprocating hook *a* carried by it, and the feeding device *s*, combined with the independent 65 laterally-reciprocating zigzag-feeding device *r*, and means to operate it at right angles to the reciprocation of the feeding device *s*, substantially as and for the purpose described.
4. The independent yoke *m*, secured to the 70 frame of the machine, the short shaft *l*, having its bearings therein, and provided with the gear *j*, and eccentric *o*, located above the cloth-plate of the machine, combined with the upright shaft *h* and pinion *i* thereon, whereby the said eccentric is made to operate an embroidery attachment, substantially as described. 75

In testimony whereof I have signed my name to this specification in the presence of two subscribing witnesses.

EDDY T. THOMAS.
